(57) **CLAIM**

The ornamental design for a copier, as shown and described.

DESCRIPTION

FIG. 1 is a top, right perspective view of a copier in accordance with my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines shown in the drawings are included for the purpose of illustrating unclaimed portions of the copier and environmental structure, and form no part of the claimed design.

1 Claim, 7 Drawing Sheets(56)
